UNITED STATES PATENT OFFICE.

HAROLD G. EYNON, OF PHILADELPHIA, PENNSYLVANIA.

ELECTRICALLY-OPERATED CENTRIFUGAL CASTING-MACHINE.

1,385,781.

Specification of Letters Patent. Patented July 26, 1921.

Application filed October 3, 1919. Serial No. 328,171.

To all whom it may concern:

Be it known that I, HAROLD G. EYNON, a citizen of the United States, residing at 3211 N. Carlisle street, Philadelphia, in the 5 county of Philadelphia and State of Pennsylvania, have invented a certain new and useful Electrically-Operated Centrifugal Casting-Machine, of which the following is a specification.

10 My invention relates to a casting machine for distributing molten metal within the mold by centrifugal force.

The purpose of my invention is to rotate the rotor (mold) of the casting machine by 15 electromagnetic action, preferably to form the rotor as one of the parts—armature or field—of an electric motor, and surround it by a stator forming the co-operating motor member with the result that the mold is rotated electrically.

20 A further purpose is to supply a part, at least of the heat of the rotor centrifugally by electrical means in order to prepare initially for the casting, and maintain uniform 25 heating conditions and avoid undue chilling during continued casting operations.

20 A further purpose is to form the end of the mold separable from its body so that the casting can be withdrawn without stopping the rotor, providing for stopping rotation 30 of the end during this removal of the casting and for rotating the end preliminary to its replacement against the body.

35 A further purpose is to rotate the rotor about a vertical axis, so that the end becomes the bottom and, preferably, to supply separate rotating means for the bottom thereof, permitting removal of the bottom and of the casting wholly or partially by gravity during 40 rotation of the body, to permit the casting to be withdrawn without stopping the rotor.

45 A further purpose is to supply a part of the lift of a removable bottom of the rotor by electromagnetic action and preliminarily to rotate the bottom electromagnetically so that it can be closed against the rotor without stopping the rotor and without rotary friction thereagainst.

50 A further purpose is to provide an overflow for the material cast through the top of the casting machine and to protect the space between the rotor and the stator against intrusion of overflow metal.

Further purposes will appear in the specification and in the claims thereof. 55

I have preferred to illustrate my invention by but one form thereof, selecting a form which is practical, efficient and thoroughly reliable and which at the same time well 60 illustrates the principles of my invention.

Figure 1 is a broken vertical longitudinal section through a casting machine embodying my invention.

Fig. 1^a is a detail side elevation of part of Fig. 1.

Fig. 2 is a section of Fig. 1 upon line 2—2.

Figs. 3 and 4 are broken sections, partly in elevation, as in Fig. 1, showing parts in slightly altered positions. 70

Fig. 3 is a detail of the shaft head shown in Figs. 1 and 3 and partly broken away.

Fig. 4 is a detail side elevation of part of Fig. 4.

Fig. 5 is a broken section corresponding to Fig. 3, but showing the stator for the bottom as of fixed height. 75

Fig. 6 is a section corresponding to Fig. 5, but with the parts in a different position.

Figs. 7, 8 and 9 are sectional perspectives showing parts of the electrical equipment. 80

Figs. 10, 11, 12, 13, 14 are diagrammatic views of electrical connections which may be used.

Similar numerals of reference indicate like parts. 85

Describing now this form, but without restricting to it:—

Taking up the description of the particular form selected, and explaining it in illustration and not in limitation:— 90

Upon a base 9 any suitable standard 10, shown here as comprising a number of pillars 10', carries at the upper end a stator 11 and the cover 12. At the center of the cover 95 a pouring funnel 13 is located.

The stator comprises one element of an electric motor-pair and may form the field or armature with equal suitability. In order to accommodate the laminated iron 100 plates 14, forming the cores 15 about which the windings 16 of the stator are wrapped, the bore 17 of the stator is counterbored at 18, and a removable annular cap 19 is provided so that both the plates and the windings inclosing them can be inserted from the top. The stator is open at the center at 20 and is provided with a base 21 and a flange 105

21', forming a seat with which the upper ends of the pillars 10' engage.

The motor is preferably of the induction type, using a rotary field which may be supplied by single phase, or by multi-phase current. The connections shown are two phase three-wire at 22, through switch S and transformer T. If desired the two phases may be kept wholly separate by the use of 10 four wires, as is well known.

Within this stator, which for convenience of description I will regard as the field, is mounted a rotor comprising a cylindrical shell 23, having a lining 24, which forms the 15 body of the mold. The shell is shown as flanged at 25, to provide upon its under surface a bearing for the balls 26, the lower part of whose race is formed in a bearing annulus 27, resting upon or within the stator, so that the ball bearings will be capable 20 of supporting the rotor. The flange 25 forms the lower limit of an annular groove 28, whose upper limit is formed by the outwardly extending flange 29 of the lining 24, 25 which flange is extended at 30 to cover and protect the space 31 between the rotor and stator so that any metal overflowing through the top of the rotor, as hereinafter described, will flow across the surface 32 of 30 the rotor upon the surface 33 of the stator and down into the space 34 between the stator and the casing or cover 12. From this space, outlet is provided through openings 35.

35 Within the annular space, 28, I prefer to provide separate heating and armature coils, though I recognize that the armature coil could be utilized for both functions. I believe that it is better to separate the coils 40 in position as well as in the function.

It is more convenient to place these coils at the upper end of the rotor and the heat from the heating coil is most needed at this point to maintain uniform temperature 45 throughout the mold.

The heating coil 36 is, of course, next to the shell and may be connected with its source of current through the conductors 37, bands 38, brushes 39, switch S' and any suitable exterior connections. The heating coil 50 36 is separated from the armature coils by a ring 40, upon which the laminated iron armature plates 41 and conductors 42 are mounted. These armature conductors may 55 be short-circuited to advantage. This is intended to represent a conventional type only, and applicant believes himself entitled to cover electromagnetic rotation of the mold and electric heating thereof broadly.

60 It will be noted that the field windings 16 are located very slightly higher than the armature winding 42. The purpose of this is to slightly lift the rotor when the current is on, so as to partly if not wholly relieve 65 the bearings from weight and consequently

from friction. Any suitable bearings 43 may be inserted at the side to receive lateral thrust during rotation, but my experience has been that the armature is self-centering and therefore requires no such bearing.

The lining 24, the "body" of the mold, is 70 changed for different sizes and shapes of casting. Its upper end is internally flanged at 24' to a radial depth corresponding with the minimum thickness of the completed casting 75 and all metal poured beyond the quantity required for this thickness of casting, overflows as previously indicated.

I make the end of the mold removable; and when the axis is vertical, this "end" becomes the bottom of the mold. The bottom 44 for the lining 24 thus becomes the bottom for the mold. This vertical arrangement, 80 with vertical movement of the bottom, permits the casting to be dropped out, with the dropping of the bottom, or at least the removal of the casting is assisted by gravity.

In the position shown in Fig. 1, the bottom 90 is closed against the mold body, with the chamfered upper surface 45 of the bottom in engagement with the chamfered lower edge 46 of the mold body 24, in which position the centrifugal casting machine is ready to receive a charge.

The bottom 44 is shown as moved vertically by conventional means in the form of a supporting shaft 47 and a lever 48, foot-pressed through a pedal not shown, so that it may occupy any position between that shown in full in Fig. 1 and the dotted position in that figure. The distance between is in excess of the height of the intended casting, so that the casting can be removed freely through the bottom of the lining 24 comprising the mold.

The mold bottom 44 is rotatably supported upon the top of the shaft 47 by means of bearings 49, 49' engaging on opposite sides of a cap plate 50 and against the interior surfaces of the plates 51 and 52 of the bottom. The cap plate is given slight vertical play upon shaft 47 while rotation upon it may be prevented, if desired, by a key 53 fitting into a slot 54, in length exceeding the key length. This construction conventionally provides vertical movement of the cap 50 with respect to the shaft and rotary movement between the bottom 44 and the cap.

The upper plate 51 and a lower plate 52 are united through flanges 55 and 56. The former is annularly grooved to receive armature plates 57 and windings 58 to make the bottom in its entirety act as an armature with respect to a field winding, preferably 120 separate from that rotating the mold and most desirably two fields 59 and 60 which are adapted to operate separately, but can be used together. The armature windings are 125 short-circuited, but the field windings are 130

connected by leads 61, 62, 63 and 61', 62', 63' through an automatic switch 64 with two phase current supply from transformer T', so that energization of the three leads for either field will set up a rotary field for the bottom as with existing two phase induction motors. The manner of connection for this purpose is well known.

The fields 59 and 60 in Figs. 1, 3 and 4 are carried by a yoke 65 upon the upper part of the shaft 47. They are separated by annulus 66 and are capped by plate 67, but in Figs. 5 and 6 are vertically stationary.

The yoke is prevented from rotation in each case by engagement of the ears 68, 68' within slots 69 of the supports. In Figs. 1 and 3 the entire shaft 47, head 50, yoke carrying the field windings and mold bottom carrying the armature for these windings may be lifted and lowered as a unit through the pedal lever; but in Figs. 5 and 6 the field is fixed, the ears 68 resting upon shoulders 70.

The armature of the mold bottom can be rotated by current in either of the field windings 59 or 60, or by both together. The lower 60, is intended to provide the initial rotation and the upper one, 59, is intended to continue the rotation and at the same time lift the mold the short distance between the positions shown in Fig. 3 and in Fig. 1, when the mold bottom has reached the speed of the mold and it is desired to close the bottom against the mold.

The lever 48 carries contacts 71, 72, 73, to which the conductors 61, 62 and 63, respectively, are connected, and contacts 71', 72', 73' with which the conductors 61', 62', 63', respectively, are connected.

It will be noted that I have again shown two-phase three-wire connections, corresponding to Fig. 13, preferring these because they simplify the illustration and reduce the number of wires and the number of contacts in each set upon arm 48 and switch 64, but recognizing that the usual connection keeps the phases separate as in Fig. 14. This can be used with four wires and four contacts per set.

All of these contacts lie upon the end 74 of the lever 48, which lever is pivoted at 75 upon a fixed member and is extended beyond the lever at 76. This pedal end of the lever passes through a guide 77 having an offset and shoulder at 78, between the two parts 79 and 79' of its path.

The contacts upon arm 74 are shown at the lowermost position of the arm in Figs. 1 (dotted) and 10 as all engaging a plate 80 short-circuiting the fields 59 and 60.

As the arm 74 is raised the contacts upon it pass from the plate 80, and, during the further progress of the arm, engage fixed contacts upon the switch board 64 to successively energize the fields 60 and 59. The

fixed contacts 81, 82, 83 are connected with the terminals of a transformer T' so as to supply two-phase current to the field 60, energizing it and causing rotation of the rotor bottom through it, but without lifting 70 effort. This position, shown in Fig. 4, may conveniently coincide with the engagement of arm 76 with the shoulder 78, so as to provide a mechanically-interposed dwell due to shoulder 78 at this point while the 75 bottom is being speeded up electrically.

As the pedal is pushed to the left in Fig. 1^a to release its arm 76 from the shoulder 78 and is then pressed further to press this arm down in the part 79' of the guide, the 80 arm 74 of lever 48 is lifted further to disconnect the movable contacts 71, 72, 73 from the fixed contacts 81, 82, 83 and to bring the movable contacts 71', 72', 73', into engagement with other fixed contacts 81', 82', 83' 85 which are also energized from the two-phase transformer T'.

This movement deenergizes the field 60 and energizes the field 59, bringing the parts to the position seen in Fig. 3. The 90 field 59 also tends to rotate the bottom, but, being higher than the armature part of the bottom, at the same time immediately tends to lift the bottom and consequently lifts it into the position seen in Fig. 1 against the 95 mold.

It will be obvious that one field could be used for the bottom, instead of the two shown, particularly if it be located "high" so that it would tend to lift all the time, the 100 final mechanical lifting movement then bringing the rotating bottom, already raised by the field, into engagement with the mold and the electro-magnetic force which holds the bottom "high" being effective to hold 105 the bottom resiliently against the mold.

It will be further evident that the field—single or double—could be used merely to rotate the bottom, the lifting into contact being wholly mechanical; and that the 110 "dwell" provided mechanically by the shoulder 78 can be provided in other ways by other constructions or merely by the care of the operator.

In operation, starting with the parts as in Fig. 1, the mold is heated by the coil 36 through any suitable application of electricity, direct or alternating, through the brushes 39 and the rings 38. This heating may be so distributed as to heat the entire 120 mold, for starting or during operation, or preferably only at the top of the mold to keep the upper and more exposed part of the mold up to temperature, and maintain uniform temperature throughout, preventing undue chilling by reason of the high rate of speed attained.

The current is turned into field 16 to rotate its armature and hence the mold exclusive of the bottom. The bottom may be 130

thrust to position of Fig. 3 and lifted to place, as in Fig. 1, by energization of the field 59, either before the rotor has been speeded up or subsequently thereto. If 5 afterward the rotor bottom should be speeded up to approximately the speed of the mold before energization of field 59 (as distinguished from field 60) is utilized to lift the rotor bottom into position in engagement with the rotor body.

The parts are now in position for casting. A charge is inserted through the funnel top which may either be measured to size or may be adjusted by overflow of any excess over 15 the top of the mold lining and out through the outlets 35. As soon as this casting has had sufficient time to set and cool, which means almost immediately, the rotor bottom is lowered. If for any reason the casting 20 is not sufficiently contracted to drop, opening the bottom gives opportunity for additional cooling. If the casting has been sufficiently cooled before the bottom has been lowered, the casting lowers with the bottom 25 and the entire bottom along with the yoke and the field carried by it may be lowered to the dotted position in Fig. 1, giving room for removal of the casting. As the bottom drops the short-circuiting of the fields (Figs. 30 1, 3 and 10) or the momentary reversal of the fields as in Fig. 12 quickly stops the rotation of the bottom and of any casting carried by it.

I recognize that mechanical brakes would 35 be effective to stop the rotation of the bottom but prefer the electrical brakes described because of their greater simplicity in application.

In the meantime, the rotor is retained at 40 speed. In the connections shown, the energization of the field 16 is constant. As soon as the casting has been removed, the pedal-operated lift is applied, lifting the bottom to the position in Fig. 4 just below that 45 shown in Fig. 3, with the pedal arm 77 resting upon shoulder 78. Current is here supplied to the field 60 to bring the bottom up to speed and subsequently, with further lifting by the field 59, to lift the rotor bottom into engagement with the rotating rotor body, ready for repeating the operation.

It will be evident that there is great variety in the means for applying the power to the several rotating parts whether mechanically or electrically; and that, where 55 this is done electrically there is also a wide range in electric motor application to this art, best exemplified by making the rotor one of the motor parts; also that the automatic 60 mechanism for making the various connections can be applied through movement of any of the moving parts; also that the electrical connections can be made separately by hand instead of by automatic means; also 65 that the field or fields for the rotor bottom

need not be raised and lowered with it, but may be stationary and the rotor bottom be brought within their zone by its vertical movement alone; also that many other features may be varied to meet the preferences 70 of the individual designer.

In Figs. 5 and 6 the construction is varied in several particulars from that of Figs. 1-4. Two fields 59 and 60 are shown for the bottom of the casing viewed as an armature, 75 but the fields are fixed instead of being carried by the yoke 65. At the bottom of the plunger position, the contacts upon arm 48 do not engage with a short-circuiting plate 74 because the fields remain in their positions 80 and short-circuiting these fields would not have the same effect upon the armature in its lowered position. It would still affect the casting, viewed as an armature, as is true to a less extent in Figs. 1-4. 85

As the bottom (armature) moves upwardly and comes to nearly the position shown in Fig. 5, the movable contacts 71', 72', 73' engage the contacts 81', 82', 83' and energize the lower field, 60, starting rotation of the armature. As in Figs. 1-4 this preferably corresponds with a mechanical dwell in the movement of lever 48, for example such as is provided in Figs. 1, 1^a and 4^a. When the bottom has come up to speed, 95 it is lifted to the final plunger position, as seen in Fig. 6. During this final plunger movement the contacts 71', 72' and 73' disengage from the fixed contacts 81', 82' and 83' and the contacts 71, 72 and 73 engage 100 with the fixed contacts 81, 82 and 83, energizing the field 59.

In the position shown in Fig. 6, the rotor bottom is at the height to which it would be raised mechanically by the plunger 47; but as soon as the field 59 is energized, the bottom is raised electromagnetically into close engagement with the lining 24 forming the body of the mold. The fixed contacts for the preferred form of Figs. 1-4 are shown 105 in Fig. 10 with diagrammatic connections to the transformer, intended (except as they are three-wire for simplicity, where the manufactured motors separate the phases and hence use four wires) to be typical of connections by which the fields 59 and 60 can be energized for induction motor operation or short-circuited.

In Fig. 11 the connections are shown diagrammatically, as preferred, for the structure seen in Figs. 5 and 6, the short-circuiting plate being omitted.

In Fig. 12, a series of field-reversing contacts 81², 82², 83²; 81³, 82³, 83³ is shown adapted to be used with a construction having fields 59 and 60 movable as in Figs. 1-4, and which contacts are engaged by the movable contacts 71, 72, 73, 71', 72', 73' on the downward movement of the rotor bottom, shortly below the position of the armature 130

seen in Fig. 4. In this position, the contacts are reversed, as compared with the contacts above, so as to tend to reverse the direction of rotation of the bottom (armature) and act as a brake in order that the operator may allow the armature to dwell at this point just long enough for its additional braking action to stop the rotation of the armature or of the casting, viewed as an armature, or both and may then drop the bottom; but that on the upward movement of the armature it may be moved past this point too rapidly for appreciable effect of the reversed fields upon the armature.

15 If these extra reversing contacts be placed near enough the other contacts, the reversal will have more effect in Figs. 5 and 6, upon the bottom (as distinguished from the casting) as the field 60 would then be near enough to the mold armature at the time of reversal for the reversal in its coils to have a corresponding increased braking effect upon the armature.

In Fig. 13, I have shown conventional two-phase, three-wire connections for the field coils, applicable to any of the three fields shown. The only reason for using the three-wire instead of the four-wire form is to reduce the complication in the illustration caused by the additional wiring. In Fig. 14 the conventional two-phase, four-wire connections for the fields are shown, from transformer T^2 , such as would more probably be used, keeping the phases A and B separate. In this, as in many of the other features shown, it will be obvious that the preference of the designer and the circumstances of the individual installation will control.

40 It will be noted that many of the claims are wholly independent of the presence or absence of electricity as a motive power, calling for a "rotor" which may be mechanical, fluid or electrical, but that some of the claims bring in additional structure defining the rotor as of electrical form preferred by me because of its greater ease of application and the elasticity of the drive.

Having thus described my invention, what 50 I claim as new and desire to secure by Letters Patent is:

1. In the method of centrifugal casting with a mold formed in two parts, a body and a separable end, the novelty which consists in pouring the casting with the end in position, separating the end from the mold, removing the casting while maintaining rotation of the body of the mold and replacing the end to prepare for another casting.

60 2. In the method according to claim 1, the novelty which consists in making the axis of rotation vertical so that the end becomes the bottom and the casting may be dropped from the body wholly or partially by gravity.

3. In the method according to claim 2, the novelty which consists in ceasing to rotate the end when the casting is to be removed.

4. In the method according to claim 2 the novelty which consists in equalizing the 70 temperature of the mold by heating the upper part of the mold artificially during the time that the mold is being rotated.

5. In the method according to claim 1 the novelty which consists in rotating the mold 75 or the bottom or both by coaxial electromagnetic stress.

6. In the method according to claim 2, the novelty which consists in rotating the mold or the bottom or both by coaxial electro- 80 magnetic stress.

7. In the method according to claim 3, the novelty which consists in rotating the mold or the bottom or both by coaxial electro- 85 magnetic stress.

8. In the method according to claim 5, the novelty which consists in winding the mold as the rotor of an electric motor, surrounding it by a stator and rotating by the elec- 90 tronagnetic stress between.

9. In the method according to claim 6, the novelty which consists in winding the mold as the rotor of an electric motor, surrounding it by a stator and rotating by the elec- 95 tronagnetic stress between.

10. In the method according to claim 7, the novelty which consists in winding the mold as the rotor of an electric motor, surrounding it by a stator and rotating by the elec- 100 tronagnetic stress between.

11. In the method according to claim 3, the novelty which consists in providing means for bringing the end of the mold up to speed while the body of the mold is main- 105 tained in rotation.

12. In the method according to claim 7, the novelty which consists in providing means for bringing the end of the mold up to speed while the body of the mold is main- 110 tained in rotation.

13. In the method according to claim 11, the novelty which consists in stopping the rotation of the bottom of the mold while the casting is removed, bringing the bottom of the mold up to speed and then closing the 115 bottom of the mold against the body of the mold ready to repeat the casting operation.

14. In the method according to claim 12, the novelty which consists in stopping the rotation of the bottom of the mold while 120 the casting is removed, bringing the bottom of the mold up to speed, and then closing the bottom of the mold against the body of the mold ready to repeat the casting operation.

15. In the method according to claim 6, the novelty which consists in sustaining part of the weight of the mold electromagnetically.

16. In the method according to claim 9, 125

the novelty which consists in sustaining part of the weight of the mold electromagnetically.

17. In the method according to claim 15, 5 the novelty which consists in utilizing a motor field to rotate the mold as an armature and placing the field high with respect to the armature to effect the lifting.

18. In the method according to claim 16, 10 the novelty which consists in utilizing a motor field to rotate the mold as an armature and placing the field high with respect to the armature to effect the lifting.

19. In the method according to claim 13, 15 the novelty which consists in causing the final closing movement of the end by electromagnetic pull.

20. In the method according to claim 14, 20 the novelty which consists in causing the final closing movement of the end by electromagnetic pull.

21. In the method according to claim 19, the novelty which consists in surrounding the end, as an armature, by a motor field which, 25 in an axial direction, is nearer to the body of the mold than is the end at the time this final closing movement is to be effected, and closing the end against the body by the axial pull of the field.

30 22. In the method according to claim 20, the novelty which consists in surrounding the end, as an armature, by a motor field which, in an axial direction, is nearer to the body of the mold than is the end at the time 35 this final closing movement is to be effected, and closing the end against the body by the axial pull of the field.

23. In the method according to claim 3, the novelty which consists in stopping rotation 40 of the mold end by electromagnetic stress after the end has been separated from the mold.

24. In the method according to claim 7, the novelty which consists in stopping rotation 45 of the mold end by electromagnetic stress after the end has been separated from the mold.

25. In the method according to claim 13, the novelty which consists in stopping rotation 50 of the mold end by electromagnetic stress after the end has been separated from the mold.

26. In the method according to claim 14, the novelty which consists in stopping rotation 55 of the mold end by electromagnetic stress after the end has been separated from the mold.

27. In the method according to claim 23, the novelty which consists in subjecting the 60 mold end, as an armature, to the influence of a motor field and short-circuiting or reversing the field.

28. In the method according to claim 24, the novelty which consists in subjecting the 65 mold end as an armature, to the influence

of a motor field and short circuiting or reversing the field.

29. In the method according to claim 25, the novelty which consists in subjecting the mold end as an armature, to the influence 70 of a motor field and short circuiting or reversing the field.

30. In the method according to claim 26, the novelty which consists in subjecting the mold end as an armature, to the influence 75 of a motor field and short circuiting or reversing the field.

31. In a centrifugal casting machine, a 80 rotor mold, an electric armature, and bearings for the armature supporting it, in combination with a field for the armature, electromagnetically centered above the electromagnetic center of the armature and tending to lift the armature with respect to its bearings. 85

32. In a centrifugal casting machine, a rotor having a vertical axis and carrying a mold, bearings therefor upon which the rotor is adapted to rest and electromagnetic means for rotating the rotor and for tending to lift the weight of the rotor from the 90 bearings.

33. In a centrifugal casting machine, a rotor carrying a mold open at one end, a closure for the end, means for rotating the 95 mold and separate means for rotating the closure, permitting it to be stopped when desired while the mold is being rotated.

34. In a centrifugal casting machine, a 100 rotor and a mold carried thereby, having an open end in combination with a closure for the end, means for moving the closure into and out of contact with the mold, means for rotating the mold and separate means for rotating the closure, permitting it to be 105 stopped when desired while the mold is being rotated.

35. In a centrifugal casting machine, a 110 rotor, a mold carried thereby having a vertical axis, a separable bottom for the mold and means for dropping the bottom and for stopping its rotation, while maintaining rotation of the mold.

36. In a centrifugal casting machine, a 115 mold, a bottom therefor, a support for the bottom upon which the bottom is rotatable and axially movable, means for moving the bottom into proximity to its closing position and electromagnetic means for lifting the mold bottom into final engagement with 120 the mold.

37. A centrifugal casting machine having a continuously rotating rotor with a vertical axis and carrying a mold, in combination with a bottom rotatable at desired intervals, movable from the said rotor for withdrawal of the castings during the rotation of the mold, and separate means for rotating the bottom, which bottom is adapted to be stopped while the rotor is being rotated. 125 130

38. A centrifugal casting machine having a continuously rotating rotor with a vertical axis and carrying a mold, in combination with a bottom rotatable at desired intervals, movable from the said rotor for withdrawal of the castings.

39. In a centrifugal casting machine, a centrifugal rotor mold in combination with a bottom therefor adapted to be rotated separately from the mold and to be stopped at desired intervals while the mold is being rotated.

40. In a centrifugal casting machine, a vertical rotor mold having an open bottom, a removable bottom therefor adapted to be dropped while the rotation of the rotor is maintained and separate means for lifting the bottom close to the mold and for closing it against the mold.

41. In a centrifugal casting machine, a rotor upon a vertical axis carrying an open-bottomed mold, means for turning the rotor, a movable bottom for the mold, itself comprising a rotor, a stator therefor, the rotor and stator together comprising an electric motor and current supply for the electric motor.

42. In a centrifugal casting machine, a rotor upon a vertical axis carrying an open-bottomed mold, a bottom for the mold comprising a motor rotor and a stator adapted to turn the rotor and located high with respect to the rotor to lift the bottom into final contact with the mold.

43. In a centrifugal casting machine, a rotor upon a vertical axis, an open-bottomed mold carried thereby and a vertically movable bottom for the mold in combination with electromagnetic means for rotating the bottom.

44. In a centrifugal casting machine, a rotor having a vertical axis, an open-bottomed mold carried thereby and a vertically movable bottom in combination with electromagnetic means for lifting the bottom.

45. In a centrifugal casting machine, a rotor having a vertical axis, an open-bottomed mold carried thereby and a vertically movable bottom in combination with electromagnetic means for lifting and rotating the bottom.

46. In a centrifugal casting machine, a rotor upon a vertical axis, an open-bottomed mold carried thereby and a vertically movable bottom comprising a motor armature in combination with two fields for the armature both adapted to rotate the armature and one adapted to lift it.

47. In a centrifugal casting machine, a centrifugal rotor, in combination with an electric stator for turning the rotor, a bottom for the rotor comprising an element of an electric motor and a separate stator for the bottom of the rotor.

48. In a centrifugal casting machine, a rotor upon a vertical axis, an open-bottomed mold carried thereby, a vertically movable bottom for the mold, forming a motor armature, a support therefor upon which the bottom is adapted to rotate, means for lifting and lowering the bottom and a field for the bottom carried by the support and adapted to be lifted and lowered with it.

49. In a centrifugal casting machine, a rotor upon a vertical axis, an open-bottomed mold carried thereby, a vertically movable bottom for the mold, forming a motor armature, a support therefor upon which the bottom is adapted to rotate, means for lifting and lowering the bottom, a field for the bottom carried by the support and adapted to be lifted and lowered with it and automatic means for energizing the field when the bottom reaches a predetermined height.

50. In a centrifugal casting machine, a rotor upon a vertical axis, an open-bottomed mold carried thereby, a vertically movable bottom for the mold, forming a motor armature, a support therefor upon which the bottom is adapted to rotate, means for lifting and lowering the bottom, a field for the bottom carried by the support and adapted to be lifted and lowered with it and automatic means for short-circuiting the field as it is lowered.

51. In a centrifugal casting machine, a rotor upon a vertical axis, an open-bottomed mold carried thereby, a vertically movable bottom for the mold, forming a motor armature, a support therefor upon which the bottom is adapted to rotate, means for lifting and lowering the bottom, a field for the bottom carried by the support and adapted to be lifted and lowered with it and automatic means for energizing the field as it moves up and for short-circuiting it as it moves down.

52. In a centrifugal casting machine, a rotor upon a vertical axis, an open-bottomed mold carried thereby, a vertically movable bottom for the mold, a support therefor upon which the bottom is adapted to rotate, means for lifting and lowering the bottom, the bottom forming a motor armature and field mechanism applicable to the armature, mounted upon the support, movable with the armature, adapted to rotate it and adapted to lift it relatively to the support.

53. In a centrifugal casting machine, a rotor upon a vertical axis, an open-bottomed mold carried thereby, a vertically movable bottom for the mold, a support therefor upon which the bottom is adapted to rotate, means for lifting and lowering the bottom, the bottom forming a motor armature, field mechanism applicable to the armature,

mounted upon the support, movable with the armature, adapted to rotate it and adapted to lift it relatively to the support and automatic means for connecting the rotating and lifting field mechanism successively as the bottom is lifted.

54. In a centrifugal casting machine, a rotor upon a vertical axis, an open-bottomed mold carried thereby, a vertically movable bottom for the mold, a support therefor upon which the bottom is adapted to rotate, means for lifting and lowering the bottom, the bottom forming a motor armature, field mechanism applicable to the armature, mounted upon the support, movable with the armature, adapted to rotate it and adapted to lift it relatively to the support and automatic means for connecting the rotating and lifting field mechanism successively as the bottom is lifted, providing a pause for rotation before the lifting function is applied.

55. In a centrifugal casting machine, a rotor upon a vertical axis, an open-bottomed mold carried thereby, a vertically movable bottom for the mold, a support therefor upon which the bottom is adapted to rotate, means for lifting and lowering the bottom, the bottom forming a motor armature, field mechanism applicable to the armature, mounted upon the support, movable with the armature, adapted to rotate it and adapted to lift it relatively to the support and automatic means for short-circuiting the field mechanism at lower levels and causing it to successively rotate and lift the armature at higher levels.

56. In a centrifugal casting machine, a

rotor having a vertical axis and comprising part of an electric motor, a mold carried by the rotor, a stator comprising the other motor element, a maintained supply of current for the stator, a vertically movable bottom for the mold comprising a second rotor for an electric motor and an automatically made and broken electric supply for revolving the bottom.

57. In a centrifugal casting machine, a rotor carrying a mold and having a vertical axis, a separable bottom for the mold, a support for the bottom upon which it has rotatable and axial movement, electromagnetic means for rotating the bottom and electromagnetic means for lifting it into final engagement with the mold.

58. In a centrifugal casting machine, a rotor carrying a mold, a heating coil surrounding the mold, an armature winding outside of the coil and a stator effective as a field for said armature.

59. In a centrifugal casting machine, a rotor having a vertical axis and carrying a mold, a stator therefor, the stator and rotor together forming an electric motor for rotation of the rotor, in combination with a top overflow for the mold.

60. In a centrifugal casting machine, a rotor having a vertical axis and carrying a mold, a stator therefor, the stator and rotor together forming an electric motor for rotation of the rotor, in combination with a top overflow for the mold and a flange carried by the rotor bridging the division line between the rotor and stator to carry the overflow beyond said division line.

HAROLD G. EYNON.
